UNITED STATES PATENT OFFICE

100,281

DESIGN FOR A KENNEL KEG

Marguerite A. Norton, White Plains, N. Y.

Application May 4, 1936, Serial No. 62,467

Term of patent 14 years

To all whom it may concern:

Be it known that I, Marguerite A. Norton, a citizen of the United States, residing at White Plains, in the county of Westchester and State of New York, have invented a new, original, and ornamental Design for a Kennel Keg, of which the following is a specification, reference being had to the accompanying drawing, forming a part thereof.

I claim:

The ornamental design for a kennel keg as shown.

MARGUERITE A. NORTON.
